UNITED STATES PATENT OFFICE.

THOMAS P. MORAN, OF NIAGARA FALLS, NEW YORK.

BRAKE MECHANISM FOR ROLLING LADDERS.

1,315,146.

Specification of Letters Patent.

Patented Sept. 2, 1919.

Application filed October 30, 1918. Serial No. 260,302.

To all whom it may concern:

Be it known that I, THOMAS P. MORAN, a citizen of the United States, residing at Niagara Falls, in the county of Niagara 5 and State of New York, have invented new and useful Improvements in Brake Mechanism for Rolling Ladders, of which the following is a specification.

This invention relates to such novel and 10 useful improvements in brake mechanisms for rolling ladders such as are usually employed in stores.

In carrying out the present invention it is 15 my purpose to provide a brake mechanism for rolling ladders whereby the ladder may be automatically locked against accidental movement when occupied thereby preventing the accidental shifting of the ladder from under the occupant during the use of 20 the ladder.

It is also my purpose to provide a brake mechanism for a rolling ladder which will be normally active and which may be rendered inactive by hand whenever it is desired 25 to shift the ladder along the track or guide rail. Thus the locking of the ladder against accidental movement is insured owing to the fact that immediately upon release of the hand operating means the brake 30 mechanism is automatically set in braking position.

Another object of my invention is the provision of a brake mechanism of the class described which will embrace the desired features of simplicity, efficiency and durability, 35 which may be manufactured and marketed at small cost, and which will embody comparatively few parts and being so arranged and correlated as to reduce the possibility 40 of derangement to a minimum.

With the above recited objects in view and others of a similar nature the invention resides in the construction, combination and arrangement of parts set forth in and falling 45 within the scope of the appended claim.

In the accompanying drawing:—

The figure is a fragmentary front elevation of a rolling ladder equipped with brake mechanism constructed in accordance with 50 my present invention.

Referring now to the drawing in detail 1 designates a ladder of any suitable preferred construction adapted to travel upon a track rail, while 2 designates a guide or support

ing rail arranged in a horizontal plane and 55 from which the ladder 1 may be suspended.

In the present instance, the hanger for the ladder 1 embodies a bracket 3 suitably fastened to the top rung of the ladder and projecting upwardly therefrom and 60 equipped at its upper ends with lateral bearings 4 in which are journaled the axles of wheels 5 to engage the track or guide rail 2. In the present instance, the peripheries of the wheels 5 are formed with 65 grooves which receive the rail 2 so as to form effective bearing surfaces for the wheels. Suitably fastened to the hanger 3 inwardly of and adjacent to the respective wheel bearings 4 are brackets 6 and pivoted, 70 at its bight within each bracket 6 is a bell crank lever 7 having one leg projecting upwardly and the other leg arranged in a horizontal plane extending toward the center of the hanger 3. Suitably connected 75 with the outer end of the horizontal legs of the bell crank levers 7 and formed integral with such legs of the bell crank levers are arcuate shaped brake shoes 8 having the lower ends arranged in juxtaposition 80 to the track 2 and the wheels 5 respectively so as to engage the wheels at the track in order to hold the hanger and ladder against accidental shifting movement along the rail or track 2. 85

In the present instance the upper ends of the vertical legs of the bell crank levers 7 are pivotally connected with the outer extremities of links 9, while the inner ends of the links 9 are pivotally connected to 90 each other and to the upper end of a vertical rod 10. The rod 10 projects downwardly within convenient reach of the occupant of the ladder. 11 designates a coil contractile spring arranged between the vertical legs of the bell crank lever 7. In the present instance the opposite extremities of the contractile spring 11 are connected with the upper end portions of the vertical legs 95 of the respective bell crank levers and this spring acts to hold the brake shoes 8 normally in engagement with the wheels of the carriage or hanger of the ladder. When, however, the rod 10 is pulled, the links 9 straighten out after the fashion of a toggle 100 link construction thereby swinging the bell crank levers 7 against the action of the spring 11 with the effect to lift the shoes 8 105

out of engagement with the wheels 5 thereby enabling the ladder to be shifted along the track.

From the foregoing description, it will be seen that I have provided an automatic brake mechanism for rolling ladders whereby the ladder may be held against accidental shifting at all times, and which may be operated manually to relieve the ladder so 10 that the ladder may be shifted whenever necessary or desired.

I claim:—

In combination with a shiftable ladder, a wheel support therefor and a track over 15 which said support is adapted to travel, of an automatic brake mechanism comprising

bell crank levers pivoted for swinging movement, brake shoes carried by corresponding legs of said levers respectively, a spring connected with the remaining legs 20 of said levers and acting upon the levers to hold the brake shoes normally in engagement with the wheels of said support, of links connected with the legs of said levers in which the springs are secured, and a 25 manually operable rod connected with said links and operable to swing said bell crank levers against the action of said spring to relieve the wheels from the influence of said brake shoes.

In testimony whereof I affix my signature.

THOMAS P. MORAN.
